UNITED STATES PATENT OFFICE.

RICHARD HENRY WILMER, OF SHANDON, OHIO.

GAME.

1,149,801.

Specification of Letters Patent.

Patented Aug. 10, 1915.

Application filed December 7, 1914. Serial No. 875,885.

To all whom it may concern:

Be it known that I, RICHARD H. WILMER, a citizen of the United States, residing at Shandon, in the county of Butler and State of Ohio, have invented certain new and useful Improvements in Games, of which the following is a specification, reference being had to the accompanying drawings.

My invention relates to games, and particularly to those games in which a board is employed having a plurality of stalls, and in which a marble or other like body is rolled down the board so as to lodge in any one of the stalls.

The primary object of my invention is the provision of a very simple game apparatus of this general character so constructed that the elements of chance and skill are both present, and so formed that it may be played in a number of different ways to add to or reduce the complexity of the game.

A further object of the invention is to provide a game board for the purpose stated wherein the stalls provided for the lodgment of the marbles are formed by a plurality of pins, these pins being set a distance apart slightly less than the diameter of the balls employed in the game, the pins being resilient and acting to deflect the marble or ball unless the marble or ball is projected directly between the pins, but acting also to hold the marble or ball if the latter strikes the space between the pins properly.

Other objects will appear in the course of the following description.

My invention is illustrated in the accompanying drawing, wherein—

Figure 1 is a plan view of the game board; Fig. 2 is a longitudinal section thereof.

Referring to these drawings, 2 designates a flat, smooth board which is inclined in the direction of its length, the upper end of the board 2 being supported by means of a vertical supporting member 3. The margin of the board is encompassed on all sides by a wall 4 which extends approximately about an inch above the surface of the board. Disposed at the lower end of the board and in spaced relation with the end wall 4^a thereof are a plurality of pins 5 which extend transversely across the board, the board being provided with numbers, these numbers being disposed between the pins and corresponding to the stalls formed between the pins.

The pieces whereby the game is played are 55 in the form of balls or marbles, one of these pieces being shown and being designated 6.

It will be observed that the pins 5 are spaced from each other a distance slightly less than the diameter of the piece 6, these 60 pins being so spaced, however, that if the marble or ball is projected properly it will force these resilient pins apart and will be wedged or held between the pins. If, however, the marble or ball strikes improperly, 65 as for instance, strikes upon one pin with greater force than it strikes the next adjacent pin, the marble or ball will be deflected and will be caused to rebound from the pins, and again rolling down the board will accidentally find a lodgment between any one of a pair of pins. It will thus be seen that if the ball or piece is projected with sufficient force and is properly directed, it will be forcibly disposed between two of the pins 70 and held in this position, whereas if the ball is deflected by striking one of the pins it will simply roll down on the board until it rests or finds lodgment against two of the pins.

It will be noted that the end wall 4^b which is disposed at the higher end of the board is above the level of the upper edge of the wall 4^a. Inward of the wall 4^b there will be a space, defined in any suitable manner, 85 as by being of a different color than the face of the board, this space being designated 7, and from this space, in one manner of playing my game, the ball 6 may be shot toward the pins 5. Upon the upper edge of the wall 90 4^a there will also be a space, designated 8, which will be properly defined, as by a suitable color, from which the ball 6 may be shot, but in this case the ball will strike the wall 4^b and rebound therefrom toward the 95 pins 5.

Of course it is to be understood that the board 2 may be of any desired length to give free movement to the marbles or balls 6, and to require an exertion of skill on the 100 part of the player. The walls 4, 4^a and 4^b constitute cushions against which the balls or marbles will strike and be deflected. It will also be seen that as the wall 4^b is disposed on a level above the wall 4^a, a player 105 resting his hand upon the wall 4^a can shoot the marble against the wall 4^b without the marble touching the board 2, so that the

marble may be projected against the wall 4^b with all the force necessary to return it forcibly toward the pins 5.

My game may be played in two ways, as 5 before indicated. The players may shoot from the space 7 directly toward the pins 5, or they may shoot from the space 8 against the wall 4^b and back to the pins 5, the last 10 of course, requiring the greater skill. It will of course be understood that in playing the game the player wins or makes those 15 numbers which are indicated by the stall into which his ball falls or rolls, and that preferably each player has a certain number of rolls or a certain number of balls to roll, and that his score is found by adding up the numbers he has won. The game is 20 adapted to be played by a plurality of players, the players being arranged on "sides," and the total score for each "side" indicating the winning side.

My game has a clear, unobstructed inclined plane forming a runway or board for the marbles, thus allowing the player to a 25 certain extent to control the chances of winning high numbers by his practice and skill. A line of more or less elastic pins at the lower end of the board gives the game the element of chance, while at the same time 30 these pins act as partitions for the several stalls. Unless the marble strikes squarely in the space between two pins it will be thrown out laterally, and will roll into the space between other pins. It requires con- 35 siderable skill to so roll a marble that it shall move along the board and land at the number desired, even one time in six. The element of skill and chance, as well as increased action are added to by having a base 40 space at the lower end of the board from which the marble may be rolled or shot to

ward the wall 4^b, so that the marble will go twice the length of the board before settling into a stall. The use of the head board or wall 4^b as a deflector in causing the marble 45 to rebound toward the line of pins is very effective, yet simple.

The game is interesting, can be made very cheaply, and has obvious attractiveness, and may be used in place of dice in such games 50 as pachisi, backgammon, etc.

Having described my invention, what I claim is:

1. A game apparatus, comprising an inclined board having an upstanding wall at 55 its margin, and a row of resilient pins disposed parallel to the wall at the lower end of the board and spaced therefrom, the space between said pins being numbered, and a ball movable upon the board and having a 60 diameter slightly greater than the spaces between the pins.

2. A game apparatus of the character described, having an inclined board formed with upwardly extending side walls, a row 65 of resilient pins disposed parallel to the lower end wall and adjacent thereto, the spaces between said pins being numbered, there being a "base" indicated upon the board at its upper end adjacent the wall 70 thereof, and a "base" indicated upon the upper edge of the lower wall, and balls constituting pieces with which the game is played, said balls having a diameter slightly greater 75 than the spaces between said pins.

In testimony whereof I hereunto affix my signature in the presence of two witnesses.

RICHARD HENRY WILMER.
